LUMINOUS DIAL

Rufus G. Fordyce, Chicago, Ill., assignor to
Radium Dial Company, New York, N. Y., a corporation of Delaware

Application June 2, 1933, Serial No. 673,992

11 Claims. (Cl. 40—10.5)

This invention relates to self-luminous devices and with particularity to methods and means for increasing the apparent optical delineation of self-luminous indicia or markings.

5 In various arts it is highly desirable to provide devices or mechanisms with indicia or markings which are self-luminous, and in many cases the markings must be capable of accurate visibility in subdued light or in total darkness. For example, in the automatic telephone art, which employs selectively operable dials or the like, the subscriber or calling party is very frequently required to manipulate the dial in darkened rooms, booths, etc. It has been suggested heretofore to employ on the dial self-luminous indicia or characters. When it is considered that the efficiency of a telephone plant is a function of the various holding times of the various trunks, selectors, etc., used in conjunction with the dial, it is of the 15 utmost importance that any indicia employed must be of the highest degree of visible delineation, otherwise the calling party will from time to time mistake one indicia for another, with the resultant false operation of the automatic selective mechanism. Ordinary indicia of self-luminous materials have not been adopted for universal use in automatic dial systems, probably because the apparent visible delineation of the self-luminous indicia or characters is insufficient. 20 It is a well-known fact that if a character is painted, printed, embossed or otherwise formed from ordinary self-luminous materials, the delineation or outline of the character is very difficult to determine. This may be due in part to the fact that with ordinary methods of forming the self-luminous indicia, the edges or outlines are not specially delineated with the required accuracy. However, it is also an inherent characteristic of self-luminous materials themselves 25 that they exhibit a fuzziness or blurred characteristic at the edges. This is all the more pronounced because the visible luminosity of self-luminous or phosphorescent materials is extremely low. As a result of this inherent limitation 30 certain indicia or characters are in many cases indistinguishable from one another. For example the numeral 6 is very often mistaken for the numeral 8 and vice versa; the numerals 3 and 8 are likewise difficult to distinguish. It is obvious, therefore, that the use of ordinary self-luminous indicia on a telephone dial or the like, may be the cause of numerous wrong connections, resulting from the fact that the calling party is 35 unable readily to distinguish one numeral or letter from another. The disadvantages set forth above in connection with automatic telephone dials are also, to a greater or less degree, prevalent in other arts where self-luminous indicia are employed.

60 Accordingly, it is a principal object of this in-

vention to provide a method and means for increasing the apparent sharpness of delineation of self-luminous indicia or markings on dials or other similar devices.

A feature of the invention relates to the combination of a carrier having thereon a series of self-luminous markings such as indicia or the like, and optical means for enhancing the apparent delineation of such indicia when viewed in a subdued light or in total darkness. 5

Another feature of the invention relates to a dial or similar device which is provided with self-luminous characters or indicia arranged in groups, in conjunction with an optical system for each group, whereby the apparent delineation of the 15 characters in each group is materially enhanced. 10

A further feature relates to an attachment for automatic telephones or the like comprising in combination a carrier of self-luminous indicia, and a lens carrier having a plurality of similar 20 short-focus lenses, one for each group of indicia.

A further feature relates to a dial carrying a series of self-luminous indicia arranged in groups, in conjunction with a series of lenses, one for each group, with the lenses proportioned in size 25 to the size of each group, and having a predetermined resolving power whereby the apparent delineation of the indicia is materially enhanced.

A still further feature relates to a dial having self-luminous indicia, in conjunction with light- 30 reflecting and refracting means for increasing the apparent delineation of said indicia.

A still further feature relates to the novel organization, arrangement, and relative location and proportioning of parts whereby a cheap dial 35 attachment for automatic telephones or the like is provided having a maximum of visibility in subdued light.

Other features and advantages not specifically 40 enumerated will be apparent after a consideration of the following detailed description and the appended claims.

While the invention will be disclosed herein as 45 embodied in a dial for automatic telephone systems and the like, it will be understood that this is done merely for the purposes of illustration and explanation and not by way of limitation, the inventive concept being capable of embodiment in any situation requiring self-luminous markings having maximum visual delineation. 50

Accordingly, in the drawings, Fig. 1 is a top plan view of the member carrying the self-luminous markings;

Fig. 2 is a plan view of a rotatable member that 55 may be used in conjunction with the member of Fig. 1;

Fig. 3 is a top plan view of a lens carrier to be used in conjunction with the member of Fig. 1;

Fig. 4 is an elevational view partly in section, 60

showing more clearly the relation between the movable dial and the fixed dial;

Fig. 5 is a top plan view of Fig. 4;

Fig. 6 shows a preferred modification of the embodiment of Fig. 4;

Fig. 7 shows a still further modification of the embodiment of Fig. 4; and

Fig. 8 is a detail sectional view of one manner of fastening the lenses in position.

Referring more particularly to Figs. 1 to 4, the numeral 1 represents a rotatable dial such as is ordinarily employed in automatic telephone systems and comprises a series of finger holes 2 to 11 inclusive. The construction of this dial forms no part of the invention and it suffices for the present, the dial is provided with the usual mechanism whereby during rotation it controls the operation of the usual automatic selective switch mechanism. In accordance with standard practice, each of the holes 2 to 11 is associated with a group of letters or numerals.

Adapted to surround the dial 1 is an annular-shaped channel member (Fig. 4), of metal, fibre, or other suitable material preferably, although not necessarily having its inner surface blackened or otherwise rendered non-reflecting. Fastened to the bottom of the channel member 12 is an annular strip 13 which serves as the carrier for the self-luminous markings or indicia 14.

As shown more clearly in Fig. 1, the self-luminous markings are arranged in groups, there being a group associated with each of the finger holes 2 to 11 inclusive. The member 12 is so mounted with relation to the member 1 that when the latter member is in its normal position, the finger hole 3 will be in radial alignment with the characters A-B-C-2, the hole 4 will be in radial alignment with the characters D-E-F-3, and so on, with the remaining groups of characters.

Attached to the top of the member 12 is another annular member 15 of metal, fibre, or suitable material. The member 15 is provided with a series of openings in which are positioned lenses 16 to 25 inclusive. The member 15 is positioned so that the lens 17 is directly above and in optical alignment with the characters A-B-C-2; the lens 18 is directly above and in optical alignment with the characters D-E-F-3, and so on for the remaining lenses. Any convenient means may be employed for fastening the lens carrier 15 to the member 12, and similarly, any convenient means may be employed for fastening the individual lenses in place in the carrier 15. For example, the member 15 may consist of two separate annular plates having aligned openings to receive the lenses, with the edges of each lens clamped between the opposite sides of the plates. On the other hand, the carrier 15 may have its outer and inner circular edges threaded as indicated by the numerals 26, 27 (Fig. 8), and the walls of the member 12 may likewise be threaded so as to enable the lens carrier 15 to be screwed into position. Likewise, if desired, the lenses may be mounted in individual circular carriers which may be individually and removably fastened in the member 15.

As set forth above, the characters 14 are formed of self-luminous materials such as a paint containing phosphorescent materials, radium-luminous materials, or the like, and any well-known method of applying these self-luminous indicia to the member 13 may be employed.

As indicated in Fig. 1, these self-luminous characters when viewed with the naked eye, in subdued light or in total darkness, have blurred out-

lines, and if the characters in each group are relatively closely spaced, they tend to coalesce visually, thus further reducing their visual delineation. On the other hand, with the employment of lenses 16 of a short focal length, when each group of self-luminous indicia is viewed through its associated lens, the visibility and delineation of each individual character are materially enhanced, as indicated in Fig. 5 of the drawings. While the explanation of this phenomena is not clearly understood, it may be due to the fact that the lenses have a resolving power which enables the body of self-luminous material in each character to be accurately imaged without imaging the irregular self-luminous particles around the edge of each character. In any event, numerous experiments prove that the use of self-luminous characters in conjunction with short focal lenses enables the characters to be positioned in closer array without rendering them blurred or vague to the eye when viewed through the lenses. Quite apart, therefore, from the increased visibility or delineation of each character there is rendered possible a saving in luminescent material, since the self-luminous characters may be grouped closer together and may be of much smaller size than is possible where they are to be viewed in the ordinary manner with the naked eye.

If desired, the lenses may have a predetermined magnifying power so as further to increase the apparent spacing and/or delineation of the self-luminous characters. Preferably, however, each lens is proportioned in size in accordance with the size of each group of characters, so that it is impossible to view one group of characters through a lens associated with another group of characters. In other words, each lens is designed as to focal length and aperture, so that the apparent delineation of the individual characters in each group is materially increased.

Instead of mounting the designation strip 13 in a plane parallel to the dial 1 as in Figs. 1 to 5, this designation strip may be mounted at an angle to the dial so as to enable all the indicia to be viewable simultaneously through the respective lenses, from a common point. Thus, as indicated in Fig. 6, the strip 13 carrying the self-luminous indicia 14 is attached to the annular channel member 12 at a slight angle. Similarly, the individual lenses 16, 17, etc., are mounted substantially parallel to the strip 13 so that an observer's eye at the point P, for example, is capable of viewing all the indicia 14 simultaneously through the respective lenses. While Fig. 6 shows one specific manner of mounting the designation strip and the lenses at an angle to the axis of the dial, it will be understood that this is merely illustrative, and that any other well-known manner of positioning these parts in desired relation as set forth may be employed.

Instead of viewing the indicia directly through the associated lenses, it may be desirable to interpose a reflector or mirror between the indicia and the lenses. Thus, as shown in Fig. 7, the annular channel member 12 carrying the individual lenses 16, 17, etc., is provided with a reflecting plate 28, which is preferably of a polished metal or the like, although, if desired, a glass mirror may be employed. The designation strip 29 carrying the indicia instead of being in the form of a flat annular disc as in Figs. 1 to 5, is in the form of a cylinder attached to the inner wall of the annular member 12. Thus the indicia on the member 29 are in planes at right angles to the

- axes of the various lenses. By means of the reflecting member 28, however, the indicia can be seen through the individual lenses. It is preferred, therefore, that the reflector 28 be mounted at an angle of approximately 45° to the plane of the lenses and to the plane of the indicia. By this arrangement the optical distance between the indicia and the lenses is effectively increased. It will be understood, of course, that the lenses 10 in the embodiment of Fig. 7 may be mounted parallel to the reflector 28, as described above in connection with Fig. 6, so as to enable the reflected indicia to be viewed simultaneously from a common point.
- 15 While various specific arrangements and materials have been mentioned hereinabove, it will be understood that the invention is not limited thereto. For example, the term "self-luminous" as employed herein, is intended to cover any 20 mixture containing a phosphorescent, a radium luminescent compound, or similar materials. Similarly, while a single lens is shown associated with each group of indicia, this is merely illustrative and, if desired, a combination of lenses 25 may be employed. It will be also understood that the various groups of indicia, instead of being mounted on a single plate or strip 13, may be mounted on individual strips so as to be replaceable from time to time. If desired, a protective 30 covering in the form of an annular strip of celluloid or other transparent material may be positioned over the lenses to protect them from scratching, breaking, etc.
- Various other changes may be made without 35 departing from the spirit and scope of the invention.
- What is claimed is:
1. In a device of the character described, a rotatable dial, a carrier surrounding said dial having thereon a plurality of self-luminous indicia, a plurality of short focus lenses, and annular means for mounting each lens a predetermined fixed distance from a corresponding area of said carrier for resolving the light from the 45 indicia to enhance the visual delineation thereof.
  2. In a device of the character described, means defining an annular channel, a strip carrying radium-luminous material positioned within said channel, closure means for said channel 50 and a plurality of spaced short-focus lenses mounted in said closure means in predetermined spaced relation to said strip.
  3. In a device of the character described, the combination of an annular channel member, another member carrying a series of self-luminous indicia, said other member being mounted within said channel member at an inclined angle to the axis of said annular member, a plurality of lenses, and means for mounting said lenses in optical 55 alignment with said indicia.
  4. In combination, a rotatable member, a fixed member surrounding said rotatable member, a strip carried by said fixed member at an inclined angle to the rotational axis of said rotatable member, indicia on said strip, and a plurality of lenses mounted each in optical alignment with associated indicia, whereby all said indicia may be simultaneously viewed from a common point through said lenses.
  5. In combination, a rotatable selective device 60 having a plurality of selecting members positioned therearound, a fixed designation dial surrounding said member and having a plurality of groups of self-luminous indicia, each group being in alignment with a corresponding one of said members, said indicia being mounted in a plane at an inclined angle to the plane of rotation of said dial, a plurality of short-focus resolving lenses each in optical alignment with one of said groups of indicia, and reflecting means between the indicia and lenses to enable the reflected indicia to be 65 viewed through the lenses.
  6. In a device of the character described, the combination of an annular channel shaped member, self-luminous indicia arranged in spaced groups on the interior of said member, closure means for said channel shaped member having a plurality of spaced openings therein, a short-focus lens mounted in each opening in optical alignment with a corresponding group of indicia, said lenses and closure member cooperating 70 with said channel member to substantially completely enclose said indicia.
  7. In combination an automatic telephone dial, a member surrounding said dial said member carrying a plurality of self-luminous indicia arranged in radial groups, a plurality of short focus lenses, means for mounting each lens a predetermined fixed distance from a corresponding one of said groups and in optical alignment therewith, and light reflecting means between said indicia and 75 said lenses for reflecting the light from each group through the corresponding one of said lenses, said reflecting means being mounted at an inclination to the axis of rotation of said dial.
  8. In combination a rotatable dial, a strip carrying a plurality of self-luminous indicia arranged in spaced groups, a plurality of short focus lenses, means for mounting said lenses at an inclination to the axis of rotation of said dial 80 so that all said indicia may be equally viewed through the lenses from a single point, the distance of said lenses from said indicia and the focal length and aperture of the lenses being so proportioned as to increase the apparent delineation of said indicia.
  9. In combination, a selective rotatable dial, a designation member surrounding said dial and fixedly mounted with relation thereto, a plurality of spaced groups of self-luminous indicia on said member, a plurality of short-focus lenses, and common means on said member for fixedly mounting each lens in alignment with a corresponding one of said groups and at a predetermined distance therefrom, said means substantially completely enclosing said indicia.
  10. In combination, a carrier bearing thereon in localized areas self-luminous indicia, a plurality of short-focus lenses, one associated with each area for increasing the apparent delineation of said indicia, means for mounting said lenses a predetermined fixed distance from each of said areas, and means extending upwardly of said carrier for supporting said lens mounting means.
  11. In combination, an annular carrier bearing thereon in localized areas radium-luminous indicia, a light-collecting and resolving member associated with each area for enhancing the discernibility of said indicia, and annular support means for supporting said members a predetermined fixed distance from their associated areas.

RUFUS G. FORDYCE.
